SEAT BACK

Robert G. Brooks and Robert E. Williams, Chicago, Ill., assignors to National Seating Company, Mansfield, Ohio, a corporation of Ohio

Application April 22, 1953, Serial No. 350,449

3 Claims. (Cl. 155—179)

This invention relates as indicated to seat backs and more particularly to an improved back designed for use in seat constructions such as commonly found in airplanes, railroad passenger coaches, and long distance buses, intended to seat two persons in side-by-side relation.

The familiar seating arrangement of such carriers consists essentially of a center aisle extending longitudinally of the carrier body, such as a bus coach, and longitudinally spaced seat units to each side of this aisle, each designed to accommodate two persons seated side-by-side. Such seat units, comprised of generally horizontal and generally vertical support portions, may be unitary in whole or in part or may comprise two closely adjacent individual seats, all seats, however, facing in a forward direction parallel to the longitudinal axis of the carrier body. As a result, passengers seated alongside each other normally face in parallel directions and this characteristic, coupled with the proximity of the two persons, precludes any individual feeling of separation. Center arm rests and ribs assist in tending physically to separate the passengers, but their mental awareness of each other's presence remains, since each is within the other's normal field of vision though facing straight ahead.

It is a primary object of our invention to provide back support means for use in double seat structures which affords psychological, as well as physical, separation of the two persons seated therein.

It is a further object of our invention to provide such back support means whereby the two passengers seated side-by-side are caused normally to face slightly away from each other, thus removing each from the other's normal range of vision while facing directly ahead.

An additional object is to provide seat backs of this nature which may readily be manufactured and used with existing seat constructions.

A further additional object is the provision of a molded rubber seat back having a laterally offset concave surface whereby such back, when mounted at the rear edge of a seat, will face slightly to one side thereof.

Other objects and advantages will become apparent as the following description proceeds.

To the accomplishment of the foregoing and related ends, the invention, then, comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a view in perspective of a seat construction provided with our improved back support means;

Fig. 2 is a horizontal section as viewed from the plane of line 2—2 in Fig. 1;

Fig. 3 is a top plan view showing two persons occupying the seat; and

Fig. 4 is a transverse section illustrating the preferred

2

cross-sectional shape of an individual molded rubber back.

Referring now to the drawing in detail, the seat unit shown in Figs. 1 to 3 will be readily recognized as of the type now commonly used in long distance buses, railroad passenger coaches, airplanes and the like, to seat two persons in side-by-side relation. The unit is conventionally intended to project outwardly from a wall of the carrier body at right angles to the longitudinal axis thereof, so that occupants of the seat will face generally in the direction of travel.

The unit comprises a generally horizontal seat portion 19 of requisite width, which is suitably supported at its sides by means of legs 11. Arm rests 12 and 13 are provided at such sides as in conventional construction.

5 Mounted at the rear edge of the seat portion are two resilient seat backs indicated generally at 14 and 15 which are of rectangular shape and have thickened upper transverse portions 16 and 17, respectively, to provide head rolls for the seat occupants.

10 As shown in Fig. 2, the construction includes a conventional frame for supporting the seat backs 14 and 15 in side-by-side relation with their inner sides closely adjacent at the approximate center of the seat. This frame includes the symmetrically rounded pressed metal plates 18 and 19 and the respectively associated tubular structural members 20 and 21. Each back is preferably supported independently of the other to provide an independent pivotal connection with the seat frame thereby enabling the backs to be adjusted to varying inclinations as 15 in the well-known reclining type of seat. The metal plates 18 and 19 face uniformly forwardly of the seat and their lateral edges lie substantially within a single plane which intersects the plane of the seat portion 10 in a straight line normal to the directional, or fore and aft, axis of such portion. The seat backs 14 and 15 disposed against these plates are generally similar, but are of right and left hand configuration as shown.

20 The front surfaces 22 and 23 of the seat backs are uniformly laterally curved concavely and the inner adjacent sides 24 and 25 thereof are thicker than the respective outer sides 26, 27. As a result, the two concavities formed are offset from the center of the seat, that is, they face slightly away from such center to opposite sides.

25 The center of the seat is indicated by the line A—A in Fig. 2, while the directional axes of the seat backs 14 and 15 are indicated respectively by the lines B—B and C—C. It will be seen that the axes B—B and C—C each extend at an angle α relative to the center line A—A, and that the occupants of the seat, therefore, tending normally to

30 face along these axes, will face slightly away from each other, as illustrated in Fig. 3. The central section of the back support means, due to the unequal thickness of the sides of the backs 14 and 15, is built-up, that is, it projects forwardly of the respective outer sides to separate the seat occupants physically. The backs are covered with suitable upholstery fabric, which may additionally enclose the supporting metal plates, if desired.

35 Each seat back is preferably formed of foam rubber molded to the cross-sectional shape shown in Fig. 4. The opposite front edges 28 and 29 of the rubber blank lie normally within the same plane while the front surface 30 curves uniformly concavely therebetween. The rear surface 31 is generally convex, but its axis of curvature is laterally offset relative to the axis of the curvature of the surface 30, so that the thickness of the blank will vary and one side 32 will be of greater thickness than the opposite side 33. The front and rear surfaces, therefore, face at an angle to each other, and when a blank

40 of this shape is supported by one of the metal plates 18 or 19 engaging the rear side edges in substantially the same plane, the edge 29 will project forwardly of the

edge 28 and the blank will deform to cause the concave front surface 30 to face toward a side of the seat. Molding to this cross-sectional shape enables the back to be readily installed in existing seat constructions since no modification of the conventional back supporting frame is required.

The seat backs may, however, be formed directly to the shape which they maintain in supported position, such as shown in Fig. 2, or may be modified to fit varying types of supporting frames provided each back in operative position has the offset concavity feature disclosed. It will be apparent that a double seat in accordance with our invention may comprise individual backs as shown in the drawing or a unitary back of double width provided with laterally offset concavities. Likewise, the horizontal seat portion may be unitary or comprised of two separate parts as desired.

It is to be noted that our seat backs effectively separate the occupants of a double seat without requiring any enlargement of the horizontal seat portion or other modification thereof which would require additional space for the unit. The entire seat portion ordinarily faces directly forward while the backs alone may be relied on to separate the seated persons.

Other modes of applying the principle of the invention may be employed, change being made as regards the details described, provided the features stated in any of the following claims, or the equivalent of such, be employed.

We therefore particularly point out and distinctly claim as our invention:

1. In vehicle chair construction, a rectangular substantially horizontal seat portion of such extent as to accommodate two passengers thereon, and back support means extending upwardly from the rear longitudinal edge of said seat portion, the outer side edges of such back support being substantially planar respectively with the ends of the seat portion in substantially parallel planes, a vertical central section of the back support projecting forwardly to a greater extent than the side margins of the

same, the front surface of the support to each side of such forwardly projecting section being laterally curved uniformly inwardly between the section and the outer margin at the respective side of the support, so as to form off-set concavities having divergent directional axes, whereby passengers uniformly supported by such back will normally face away from one another.

2. In vehicle chair construction, a rectangular substantially horizontal seat portion of such extent as to accommodate two passengers thereon, and a back support frame extending upwardly from the rear edge of said seat portion in each longitudinal half thereof, such frames being arranged closely together at their inner vertical margins and uniformly oriented with respect to the transverse extent of the seat portion, and a body of resilient material overlying each back support frame, such bodies being thicker at their inner vertical margins than at their respective outer margins to form generally central forwardly projecting back sections, the front surface of each body being uniformly laterally curved inwardly between its vertical margins, so that the two such surfaces define off-set concavities having divergent directional axes, whereby passengers uniformly supported by such back portions will normally face away from one another.

3. A chair construction as defined in claim 2 characterized further in that such resilient bodies are elongated molded foam rubber cushions having longitudinal margins of unequal thickness and a front surface which is curved uniformly therebetween.
